US0D1075303S

(12) **United States Design Patent** (10) **Patent No.:** **US D1,075,303 S**
(45) **Date of Patent:** **** May 20, 2025**

(54) **BRUSHLESS DRILL KIT**

(71) Applicant: **SHANGHAI HOTO TECHNOLOGY CO., LTD.**, Shanghai (CN)

(72) Inventors: **Lidan Liu**, Shanghai (CN); **Lu Zheng**, Dalian (CN)

(73) Assignee: **SHANGHAI HOTO TECHNOLOGY CO., LTD.**, Shanghai (CN)

(**) Term: **15 Years**

(21) Appl. No.: **29/883,000**

(22) Filed: **Jan. 23, 2023**

(30) **Foreign Application Priority Data**

Dec. 5, 2022 (CN) 202230814415.8

(51) **LOC (15) Cl.** **03-01**

(57) **CLAIM**

The ornamental design for a brushless drill kit, as shown and described.

DESCRIPTION

FIG. 1 is a first perspective view of a brushless drill kit showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the brushless drill kit; and,

FIG. 10 is an enlarged view of the selected portion 10 in FIG. 1.

The broken lines shown in the drawings depict portions of the brushless drill kit that form no part of the claimed design. The broken lines encircling portions of the brushless drill kit in FIG. 1 and shown in the enlarged view in FIG. 10 form no part of the claimed design.

1 Claim, 10 Drawing Sheets
